UNITED STATES PATENT OFFICE.

DANIEL J. BEMILLER, OF BUTLER, OHIO, ASSIGNOR OF ONE-HALF TO SAMUEL RITTER, OF BUTLER, OHIO.

FAN-BLOWER.

No. 927,819.

Specification of Letters Patent.

Patented July 6, 1909.

Application filed January 28, 1907. Serial No. 354,534.

To all whom it may concern:

Be it known that I, DANIEL J. BEMILLER, a citizen of the United States, residing at Butler, in the county of Richland, State of Ohio, have invented certain new and useful Improvements in Fan-Blowers; and I do hereby declare the following to be a full, clear, and exact description of the invention, such as will enable others skilled in the art to 10 which it appertains to make and use the same.

The present invention relates to fan-blowers, and it aims to provide a simple, efficient, and inexpensive device of that nature, the 15 several parts of which are detachably connected with each other, so as to permit the device to be easily and quickly taken to pieces and set up again.

The invention will be readily understood 20 from the following detailed description, and its preferred embodiment is illustrated in the accompanying drawings, in which like parts are designated by corresponding reference numerals in the several views.

25 Of the said drawings—Figure 1 is an end view of a fan constructed in accordance with the present invention. Fig. 2 is a side elevation thereof. Fig. 3 is a vertical section taken on the line 3—3 of Fig. 2. Fig. 4 is a 30 perspective view of one of the side plates of the fan casing. Fig. 5 is a similar view of the metal band connecting the side plates. Fig. 6 is a vertical section taken longitudinally through the fan casing.

35 Referring more particularly to the drawings, 7 designates the support for the blower and its driving means, and, as shown, is formed of a single casting provided with upper and lower flanges 8 and 9 and a connecting flange 10, the latter being disposed at the inner edge of the casting. The flanges 8 form the lower members of the bearings for the drive-shaft 11 of the blower, the upper bearing members being formed by a pair of 40 removable caps 12, bolted to the flanges 8. The shaft 11 carries a belt-pulley 13, which is disposed within the U-shaped recess 14, formed in the casting 7. Shaft 11 is further provided adjacent the outer end of the casting with a collar 15, which serves to limit or prevent end-play. Each of the caps 12, above referred to, preferably carries an oil-cup 16, through which a lubricating medium 45 is passed to the shaft.

50 As shown in Fig. 3, the drive-shaft extends

beyond the casting 7 and into the casing 17 of the blower, which latter comprises outer and inner plates 18 and 19, each of which is provided with a series of radially projecting ears 20, that are arranged in transversely 55 aligned pairs, the ears being perforated for the reception of the tie-bolts 21. Each side plate of the casing is provided with a vertical tangential projection 22, and further each plate is provided on its inner face with a 60 deep groove 23, arranged adjacent to its outer edge and following the contour of the plate. These grooves serve as retaining means for a resilient metal band 24, the side edges of which fit therein, the band being 65 retained in place through the action of the tie-bolts, above referred to. Owing to the resiliency of the metal from which the band is formed, it may be readily bent so as to fit in the grooves in the casing plates, the space 70 between the free ends of the band forming the discharge opening of the blower.

The drive shaft 11 carries a fan 25 within the casing 17 which is formed with a hub 75 splined or otherwise connected with shaft 80 and with the outer surface square, and upon which the fan structure is mounted. The fan structure comprises a plurality of fan blades 26 with the inner end of each blade bearing against the adjacent end of the next 85 blade and so on around the central portion of the fan, leaving a square central opening in which the square hub fits, as shown. The blades 26 are supported by angular braces so that a very rigid and substantial fan is produced, which is simple in construction and can be inexpensively manufactured. The fan is also removable from or attachable to the shaft for renewal or repairs, or to enable the fan to be reversed upon the shaft. The 90 fan blades 26 are thus arranged in the requisite tangential position relative to the shaft, as will be obvious.

The inner side plate 19 of the casing, as 95 shown in Fig. 1, is bolted directly to the flange 10 of the casting 7, while the outer plate is provided with an axial opening 27 formed therethrough, the walls of which are being drawn outwardly to form a collar 28, to which one end of the suction pipe 29 is secured, the latter being formed of a series of 100 jointed sections, as shown. The pipe 29 further includes a series of elbow joints so as to permit a turning movement of the pipe sections in different directions. The casing in- 105 110

cludes a discharge pipe connected thereto adjacent the opening formed therein and preferably extending directly upward.

Owing to the detachable connection between the several parts of the machine, it may be readily and quickly taken to pieces and put together again. It will also be seen that the entire machine includes but few parts and therefore may be manufactured at small cost, and that where a single part has become worn or otherwise injured, it may be replaced at a slight cost, thus continuing the life of the machine almost indefinitely.

What is claimed, is—

15. A fan blower comprising side and end walls, a shaft extending into the casing through one of the sides, a hub rigid with the shaft, a plurality of blades fast to the hub, having their inner ends substantially the same width as the length of the hub and their

outer ends substantially the same width as the fan casing, and their opposite longitudinal sides having a compound curvature extending from the extremities of the upper ends to the corresponding extremities of the lower ends, and bracing elements connecting the inner ends of the blades, each element being a tetrahedron with its base disposed against the inner end of the blade, the edge of each element operating to split and deflect the air in the zone surrounding the shaft, whereby the formation of a dead air cushion is prevented.

In testimony whereof, I affix my signature, in presence of witnesses.

DANIEL J. BEMILLER.
